D. GRATTAN.

SLACK ADJUSTER

Filed Sept. 26, 1925.

Patented Apr. 20, 1926.

1,581,438

UNITED STATES PATENT OFFICE.

DAVID GRATTAN, OF LOS ANGELES, CALIFORNIA.

SLACK ADJUSTER.

Application filed September 26, 1925. Serial No. 58,840.

To all whom it may concern:

Be it known that I, DAVID GRATTAN, a citizen of the United States, residing at Los Angeles, in the county of Los Angeles, State of California, have invented certain new and useful Improvements in Slack Adjusters, of which the following is a specification.

This invention relates to an improvement 10 in automatic slack adjusters for use with the air brake equipment employed on railway cars.

The object of the present invention is to provide a device of this character which is 15 of simple and durable construction, reliable and effective in operation and easy and inexpensive to manufacture and which will maintain a uniform piston travel so that the brake will be applied uniformly to every 20 car in the train, thereby eliminating jerk and shock.

A further object is to provide a device of this character which requires little or no maintenance and which involves no parts 25 or mechanism liable to get out of order or to require periodic and thorough lubrication to insure proper operation.

A further advantage resides in the fact 30 that the higher braking efficiency obtained by the present invention as organized in the braking equipment will enable the engineer to stop the train in an emergency much more quickly and will always make it possible to bring about a smooth and easy stop, 35 the shocks and jerks being eliminated, whereby the liability of accidents to persons on the train is greatly reduced.

Other objects and advantages reside in 40 certain novel features of the construction, arrangement and combination of parts which will be hereinafter more fully described and particularly pointed out in the appended 45 claims, reference being had to the accompanying drawings forming a part of this specification, and in which:

Figure 1 is a view in elevation showing 50 the manner in which the device is applied.

Figure 2 is a view in central longitudinal 55 vertical section taken on the line 2--2 of Figure 1 parts being shown in elevation for the sake of illustration.

Figure 3 is a view in cross section on the line 3--3 of Figure 2.

Figure 4 is a similar view on the line 4--4 60 of Fig. 2,

Figure 5 is a view in end elevation looking toward the right of Fig. 2, and

Figure 6 is a fragmentary detail view in perspective showing the camming element 60 for one of the pawls.

Referring to the drawings the numeral 1 designates generally the slack adjuster constituting the present invention, and this comprises a cylindrical casing 2 having brackets 3 spanning a truck bolster 4 and secured 65 thereto by bolts and nuts 5.

At one end the casing 2 has a tapering integral head 6 merging into an integral tubular guide 7. The tubular guide 7 is preferably of cylindrical form and provides 70 an elongated cylindrical guide opening 8.

A head plate 10 is secured by bolts and nuts 11 to a flange 12 formed on the end of the cylindrical casing 2 opposite the head 6 and guide 7. Centrally the head plate 10 has a guide opening 13 in which a sleeve 14 is slidably fitted. The outer end of the sleeve projects beyond the guide and the inner end of the sleeve carries a circular plate 15 which has its periphery slidably 75 engaging the inner periphery of the inner casing 2. A coil spring 16 is placed on the sleeve 14 within the cylindrical casing 2 and has one end abutting the head plate 10 and the other end abutting the circular plate 15 of the sleeve 14. The spring 16 is tensioned to force the sleeve into the cylindrical casing 2. The outer end of the sleeve 14 is closed by an integral end wall on which an apertured lug 14^a is integrally formed. To the lug 14 one end of a chain 17 is positively 80 connected and the other end of the chain is connected with the live lever L of the conventional braking equipment or if preferred to the top brake rod which connects with the 85 live lever.

An adjusting bar 18 is slidably fitted in the guide 7 and in the guide opening of the sleeve 14. The bar 18 has a flattened portion which is formed with a plurality of notches 19. A pawl 20 is pivoted, as at 21, to lugs 22 integrally formed with or suitably secured to the plate 15 and this pawl 20 contacts with the notches 19 of the bar 18.

The pawl 20 and the lugs 22 on which the same is pivoted are slidably received in a longitudinal slot 23 provided in the upper portion of the casing 2. Laterally directed camming lugs 24 are rigidly connected to the side faces of the pawl 20 and are co- 105 110

operable with inclined cam shoulders 25 provided on the walls of the slot 23.

An anchoring pawl 26 is pivotally mounted, as at 27, on the casing 2 and also co-acts with the notches 19 of the bar 18, the pawl 26 operating through a slot 18^a in the casing 2. A finger piece 28 is provided on the pawl 26 and affords a means whereby this pawl may be released and blocked when it is necessary to pull the adjusting bar 8 out as for instance when new brake shoes are being applied.

A hinged cover plate 30 is provided for the slot of the casing and the pawls and is releasably secured in position by any suitable locking or fastening means.

The portion of the casing 2 which lies between the slots 23 and 18^a provides an abutment 31 with which the pawl is engageable in certain phases of the operation that will hereinafter more clearly appear.

The dead lever D of the conventional braking mechanism is pivotally connected, as at 32, to a laterally extending arm 33 rigidly connected to one end of the adjusting bar 18.

When the brakes are applied on the train and the piston in the braking equipment of any car travels farther than it should, the chain 17 connected to the live lever will be pulled thereby and will in turn draw the sleeve 14 outwardly against the tension of the spring 16. This outward movement of the sleeve 14 further compresses the spring 16 due to the fact that the plate 15 which is rigidly connected to the sleeve and against which one end of the spring abuts moves toward the head 10 against which the other end of the spring abuts. As the sleeve 14 moves outwardly the pawl 20 is also moved outwardly, the pawl riding out of the notch with which it is engaged when it is moved to the left, as viewed in Figure 2. If the pawl 20 moves a greater distance than that which separates two adjacent notches on the bar 18, its lugs 24 will ride up the shoulders 25 and along the top of the casing 2, the lugs 24 spanning the slot 23. During this action the bar 18 is held against movement to the left, as viewed in Fig. 2, by the anchoring pawl 26.

When the brakes are released the spring 16 expands and forces the sleeve 14 inwardly. This also carries the pawl inwardly. The pawl 20 engages the bar 18 one notch to the left of the point where it has previously engaged the bar and this results in a shifting of the bar 18 to the right as viewed in Fig. 2 a distance equal to the spacing of the notches. In this way the excess of piston travel is taken up step by step. The anchoring pawl 26 does not interfere with the movement of the bar 18 to the right as viewed in Fig. 2. When the sleeve 14 and the pawl 20 carried thereby are moved to the right or inwardly of the casing 2 as far as they may the pawl

20 is engaged with the abutment 31 and thereby is held in engagement with its notch in which it is seated. The shifting of the bar 18 to the right shifts the fulcrum 32 of the dead lever D and thus compensates for the excessive piston travel. In order to facilitate the replacing of brake shoes a number of small sockets or holes 40 may be provided in the sleeve and a small lug 41 may be provided on the head of the casing. A bar or lever may be fulcrumed on the lug 41 and have one end engaged with one of the sockets 40 and used to draw the sleeve outwardly so as to compress the spring 16 to such an extent as to facilitate disengagement of the pawls from the notches in which they are seated.

The outer end of the guide 7 is obstructed by a bolt 35. Of course, this guide is slotted to permit the arm 33 to extend therefrom and connect up with the dead lever.

I claim:

1. An automatic slack adjuster for use with conventional railway brakes having the usual live lever and dead lever and comprising a casing having an elongated guide at one end, an adjusting bar slidably fitted in the guide and having a plurality of notches, a sleeve slidably fitted on the bar, spring means between the casing and the sleeve urging the sleeve inwardly of the casing, a pawl connected to the sleeve and engageable with the notches of the bar, an abutment on the casing engageable with the pawl for holding it in one of the notches of the bar when the pawl and abutment are engaged, an anchoring pawl pivoted on the casing and engageable with the notches of the bar, and a chain between the sleeve and the live lever.

2. An automatic slack adjuster for use with the conventional brake equipment having the usual live lever and dead lever and comprising a stationary casing fixed on a truck bolster and having an elongated guide at one end and a head provided with a guide opening at its other end, an adjusting bar slidably fitted in the elongated guide and connected to the dead lever, a bar having a plurality of notches, a sleeve slidably fitted on the adjusting bar in the guide opening and having a plate at its inner end, a spring between the head and the plate, a pawl pivoted on the plate and engageable with the notches of the bar, an anchoring pawl pivoted on the casing and also engageable with the notches of the bar, an abutment on the casing engageable with the first-mentioned pawl when it is in position to take up the slack, and a connection between the sleeve and the live lever.

3. An automatic slack adjuster for use with conventional railway brakes having the usual live lever and dead lever and comprising a casing having an elongated guide at

- one end, an adjusting bar slidably fitted in the guide and having a plurality of notches, a sleeve slidably fitted on the bar, spring means between the casing and the 5 sleeve urging the sleeve inwardly of the casing, a pawl connected to the sleeve and engageable with the notches of the bar, means on the casing engageable with the pawl for holding it in one of the notches of the bar 10 when the pawl and said means are engaged, and a connection between the sleeve and the live lever.
4. An automatic slack adjuster for use with conventional railway brakes having the 15 usual live lever and dead lever and comprising a casing having guide means, an adjusting bar slidably fitted in the guide means and having a plurality of notches, a sleeve slidably fitted on the bar, spring means be- 20 tween the casing and sleeve for urging the sleeve inwardly of the casing, a pawl connected to the sleeve and engageable with the notches of the bar, co-operative means between the pawl and the casing for constrain- 25 ing the pawl to exert a step by step movement in the bar, an abutment on the casing engageable with the pawl for holding it in one of the notches of the bar when the pawl and abutment are engaged, and a connection 30 between the sleeve and the live lever.
5. An automatic slack adjuster for use with conventional railway brakes having the usual live lever and dead lever and comprising a casing having a guide, an adjusting bar 35 slidably fitted in the guide and having a plurality of notches, a sleeve slidably fitted on the bar, spring means between the casing
- and the sleeve for urging the sleeve inwardly, a pawl connected to the sleeve and engageable with the notches of the bar, said 40 casing having a slot accommodating the pawl in certain of its movements, said casing and said pawl having co-operating camming means for lifting the pawl from the notches of the bar when it has moved a predeter- 45 mined distance with respect to the bar, means on the casing engageable with the pawl for holding it on one of the notches of the bar when the pawl and abutment are engaged, and a connection between the sleeve and the 50 live lever.
6. An automatic slack adjuster for use with conventional railway brakes having the usual live lever and dead lever and comprising a casing having a guide, an adjusting bar 55 slidably fitted in the guide and having a plurality of notches, a sleeve slidably fitted on the bar, spring means between the casing and the sleeve for urging the sleeve inwardly, a pawl connected to the sleeve and engageable with the notches of the bar, said 60 casing having a slot accommodating the pawl in certain of its movements, said casing and said pawl having co-operating camming means for lifting the pawl from the notches 65 of the bar when it has moved a predeter- mined distance with respect to the bar, means on the casing engageable with the pawl for holding it on one of the notches of the bar when the pawl and abutment are en- 70 gaged, and a connection between the sleeve and the live lever, said casing having a cover for the pawls.

DAVID GRATTAN.
